UNITED STATES PATENT OFFICE.

WILLIAM F. KELLY, OF ST. LOUIS, MISSOURI.

PRESS FOR MAKING PLASTER-BOARD.

967,933.

Specification of Letters Patent. Patented Aug. 23, 1910.

Application filed April 28, 1910. Serial No. 558,246.

To all whom it may concern:

Be it known that I, WILLIAM F. KELLY, a citizen of the United States, residing in the city of St. Louis and the State of Missouri, have invented a new and useful Improvement in Presses for Making Plaster-Board, of which the following is a full, clear, and exact specification, reference being had to the accompanying drawings, which form a part thereof.

My invention relates to presses used for making plaster board in which the cement, asbestos and other ingredients which enter into the composition of the plaster board are subjected to heavy pressure.

In making plaster board the ingredients are mixed and then spread in a layer in a frame or mold and are subjected to pressure by which the materials forming the plaster board are pressed into a compact dense sheet or board, and then the plaster board is removed from the frame and allowed to harden or set.

The object of my invention is to provide a press whereby the pressure to which the plaster board is subjected may be varied; and a further object of my invention is to provide a press which may be easily operated and in which the plaster board may be retained under pressure of a fixed amount; and a still further object of my invention is to provide a press in which while one plaster board is being subjected to pressure another plaster board which has already been pressed is by the action of the machine being lifted out of the frame in which it was formed.

My invention is fully shown in the accompanying drawings where similar letters are used to designate similar parts.

Figure 1 is a side view of the press; Fig. 2 is a front view with a part of the base of the press cut away so as to show the internal mechanism; and Fig. 3 is a plan view looking down on top of the press.

Referring to the figures, A is a base or table having a smooth top surface and carrying upwardly projecting columns B which support a girder portion C.

D is a shaft supported by the bracket bearings E carried by two of the columns B.

F is the pressure plate which is provided with guides f which move along the columns B.

G' represents guide bolts whose lower ends are screwed into the pressure plate F and

which project upwardly through openings in the spring plate G and which are provided with nuts on their upper ends.

H represents heavy coil springs encircling the bolts G' between the pressure plate F and the spring plate G.

J and K are levers which form a toggle which is connected to the spring plate G and the girder C, respectively, by the pins g and k.

h is the knuckle pin of the toggle formed by the levers J and K, and to it is fastened the eccentric arm L which is operated by the eccentric M attached to the shaft D. When the shaft D is made to turn the eccentric M moves the eccentric arm L toward the left of the position shown in Fig. 1 so as to straighten the toggle and thus depress the spring plate G and with it the pressure plate F. If the pressure plate F is depressed as far as it can be it will come to rest and then a further straightening of the toggle will depress the spring plate G against the resistance of the springs H, and as long as these springs remain active so that they are subject to further compression no greater pressure can be brought upon the material beneath the pressure plate F than that required to compress the springs H. By adjusting the strength of the springs H it is evident that the amount of pressure to which material beneath the pressure plate F is subjected may be regulated.

I represents stop bolts by which the amount of compression of the springs H may, when necessary, be limited. When the springs H are compressed so that the lower ends of the bolts I come in contact with the pressure plate F, a straightening of the toggle tends to move the spring plate G and the pressure plate F downward as though they were made integral.

N', N, and N'' are frames in which the plaster boards are formed. N', shown dotted in Fig. 3, represents a frame in position to be filled with material of which the plaster boards are formed; N represents a frame in position under the pressure plate F; and N'' shown in Figs. 2 and 3, represents a frame in which is a plaster board that has been subjected to pressure and which is about to be removed from the frame.

a are guides which hold the frame N in place.

b and d are stop guides for the frame N''. b' are clamps operated by the handle c by

which the frame N'' is held in place against the stops b and d .

The size of a plaster board is determined by the inside dimensions of the frames, and 5 the lower or under part of the pressure plate F projects downward and is slightly smaller than the inside of the frame N , so that when the material composing the plaster board is being subjected to pressure the lower or 10 under part of the pressure plate F enters the frame N .

P is an angle piece attached to the rear guides f of the pressure plate F . When the pressure plate F is depressed the angle 15 piece P comes in contact with the roller Q carried at the end of the arm R . The arm R is attached to the rocker-shaft S , which carries rocker arms R' provided with rollers T . The rollers T support a plate U which 20 has attached to it and projecting outwardly therefrom plungers V . These plungers pass upwardly through openings in the upper part of the table or base A of the press, and their purpose is, as shown in Fig. 25 2, to lift the plaster board that has been subjected to pressure out of the frame N'' . When the pressure plate F is depressed the angle piece P comes in contact with the roller Q and depresses the outer end of the 30 arm R so as to make the shaft S revolve through a limited angle and thus raise the rollers T at the end of the arms R' , as indicated by the dotted lines in Fig. 2, and thus raise the plungers V and lift the plaster 35 board from the frame N'' .

It is preferable to put the material of which the plaster boards are formed between metal sheets or plates in the frames in which the boards are pressed, as indicated in 40 Figs. 2 and 3, where m represents the lower metal plate, l the plaster board, and g the top or cover metal plate.

The press is driven by means of a belt passing over a pulley O loosely mounted on 45 the shaft D , but which can be made to drive the shaft D by means of a clutch attached to and carried by said shaft. The clutch consists of a part p rigidly mounted on the shaft D which carries a pin r having a 50 shank adapted to engage with an opening t in the hub or boss of the pulley O . The shank of the pin r is provided with a coil spring s which ordinarily prevents the shank from engaging with the opening t . 55 The head of the pin r presses against a collar n loosely mounted on the shaft D . The face of the collar adjacent to the pin r is at right angles to the shaft D and the opposite face is beveled as shown in Fig. 2. The 60 collar n and the part p of the clutch revolve in a casing z which is supported by one of the bearings E . Projecting upwardly through the lower part of the casing z is a pin q whose upper end is beveled to the 65 same angle as the beveled face of the collar

n . When this pin is raised its beveled end engages with the beveled face of the collar n and forces the collar to the right of the position shown in Fig. 2 and makes it press the pin r outwardly toward the pulley O so that the shank of the pin r engages with the opening t , and then the shaft D is made to revolve with the pulley O . The pin q projects upwardly through the casing z from the member x and is kept normally from 70 engaging with the collar n by means of the spring w . The member x is raised by means of the rod y when it is desired that the clutch shall operate to make the pulley O drive the shaft D .

When it is desired to make a plaster board, a frame is placed on the table A in the position of the frame N' , shown in Fig. 3, and the lower metal plate m is placed in the frame, then the materials which enter into the plaster board are spread over the metal plate m to a uniform depth and the top or cover plate g is placed in the frame on top of the material of the plaster board. The frame is then moved into the position 85 of the frame N in Fig. 3 and the clutch is operated so as to make the pulley O drive the shaft D , and through the medium of the arm L and the toggle composed of levers J and K the pressure plate F is depressed so 90 that its lower or under part enters the frame N and presses or squeezes the material therein into a hard compact plaster board. When the toggle has been nearly straightened the clutch may be operated so that the pulley 95 will no longer drive the shaft and the plaster board may be allowed to remain for some time under pressure in the frame N , or if the pulley is driven slowly the machine need not be stopped but the plaster board 100 in the frame N may be subjected to pressure only during the time that the pressure plate is depressed for one revolution of the shaft D . The pressure to which the plaster board will be subjected will depend largely 110 upon the strength of the spring H between the pressure plate F and the spring plate G . When the plaster board has been subjected to pressure the frame is moved to the position of the frame N'' of Fig. 3 and 115 clamped by means of the clamps b in place against the stops b and d . When this is done, at the next downward stroke of the pressure plate F the angle piece P will come in contact with the roller Q which will operate the arm R so as to make the shaft S revolve through a limited angle and raise the arms R' with the rollers T and thus raise 120 the frame U and the plungers V to lift the plaster board upward out of and beyond the frame N'' as shown in Fig. 2. When the plaster board and the metal plates g and m are lifted out of the frame they can be removed from the press and the plaster board 125 put in some convenient place to dry.

It is evident that by making the table A of the press large enough to receive three plaster board frames as shown in Fig. 3 one frame will be in the position of N' 5 where the material is being put in the frame, and the second frame will be in the position of the frame N where the material is either subjected to pressure or ready to be subjected to pressure, while a third frame will 10 be in the position of N'' ready to have the pressed plaster board lifted out of the frame into a position from which it can be readily removed from the press.

It is evident that the sizes of the frames 15 and strength and dimensions of the various parts of the press must be made to suit the needs of the conditions and sizes of the plaster boards to be made.

What I claim as new and desire to secure by Letters Patent, is:

1. A press for plaster boards comprising a table, a pressure plate adapted to move toward and from said table, a spring plate carried by said pressure plate and adapted to have a limited motion toward and from said pressure plate, compression springs between said pressure plate and said spring plate, means whereby said spring plate is moved to make said pressure plate move toward and from said table, and means operated by said pressure plate as it moves toward said table whereby a plaster board that has been subjected to pressure is lifted from said table, substantially as described.

2. A press for plaster boards comprising a table, a pressure plate adapted to move toward and from said table, guide bolts carried by said pressure plate, a spring plate adapted to have a limited motion along said guide bolts toward and from said pressure plate, compression springs between said pressure plate and said spring plate, a toggle whereby said spring plate is moved to make said pressure plate move toward and from said table, and means operated by said pressure plate as it moves toward said table whereby a plaster board that has been subjected to pressure is lifted from said table, substantially as described.

3. A press for plaster boards comprising a table, means whereby said toggle is operated, and means operated by said pressure plate as it moves toward said table whereby a plaster board that has been subjected to pressure is lifted from said table, substantially as described.

4. A press for plaster boards comprising a table, a pressure plate adapted to move

toward and from said table, a spring plate carried by said pressure plate and adapted to have a limited motion toward and from said pressure plate, compression springs between said pressure plate and said spring plate, means whereby said spring plate is moved to make said pressure plate move toward and from said table, plungers adapted to lift 60 from said table a plaster board that has been subjected to pressure, and means whereby said plungers are operated by said pressure plate when said pressure plate is made to move toward said table, substantially as described.

4. A press for plaster boards comprising a table, a pressure plate adapted to move toward and from said table, guide bolts carried by said pressure plate, a spring plate adapted to have a limited motion along said guide bolts toward and from said pressure plate, compression springs between said pressure plate and said spring plate, stop bolts whereby the motion of the spring plate 75 toward the pressure plate may be regulated, a toggle whereby said spring plate is moved to make said pressure plate move toward and from said table, means whereby said toggle is operated, and means operated by 80 said pressure plate as it moves toward said table whereby a plaster board that has been subjected to pressure is lifted from said table, substantially as described.

5. A press for plaster boards comprising a table having openings in the top thereof for plungers, a pressure plate adapted to move toward and from said table to one side of said openings, means whereby said pressure plate is made to move, plungers adapted to move up through said openings in said table and project above the top thereof, a frame supporting said plungers from below, and means operated by said pressure plate as it moves toward said table whereby said frame is raised, substantially as described.

In testimony whereof I have signed my name to this specification in the presence of two subscribing witnesses.

WILLIAM F. KELLY.
